UNITED STATES PATENT OFFICE.

JOHN H. BURRELL, JR., OF PHILADELPHIA, PENNSYLVANIA, ASSIGNOR OF
ONE-HALF HIS RIGHT TO FRANK D. HOWELL, OF SAME PLACE.

IMPROVEMENT IN CAR-COUPINGS.

Specification forming part of Letters Patent No. 146,650, dated January 20, 1874; application filed
July 19, 1873.

To all whom it may concern:

Be it known that I, JOHN H. BURRELL, Jr., of Philadelphia, in the county of Philadelphia and State of Pennsylvania, have invented a certain new and useful Improved Automatic Coupling for Railroad-Cars, of which the following is a specification:

The nature of my invention consists in combining, with a draw-bar of a railroad-car, a segment drop or latch for holding the connecting-link, said segment drop being hung at the extreme front of the draw-bar by a pivot, which passes through the center of the circle of which the drop forms a segment; the curved part of the drop forms a buttress, against which the link pulls in drawing the car. The object is to produce a coupling which will be self-acting, strong, and easily detached, when desired.

Figure 1 shows in plan two draw-bars with my invention attached. Fig. 2 shows one of the draw-bars in elevation, and one in vertical section. Fig. 3 shows one of the drops in elevation.

Let B B, Figs. 1 and 2, represent the draw-bars. Into the upper part of these draw-bars I place the drops C, which are pivoted at E, as shown in Fig. 2. D is the coupling-link, made in the ordinary manner. The drops C are free to move in a vertical slot made in the draw-bars for that purpose. As the link D enters the mouth of the draw-bar it comes in contact with the drop C, pushes it up, and passes beyond, so as to allow it to drop back and hold the link, as shown in Fig. 2. The holding-face of the drops C forms a part of a circle, of which the pin E is the center, so that no amount of strain ex-

erted on the coupling-link D will throw it up; yet, when it is desirable to uncouple the cars, a moderate degree of force applied to the ring H will draw it up, and thus free the coupling-link. The upper part of the segmental drop C is formed as shown so that it may be raised into the position indicated by dotted lines in Fig. 2, and remain in that position until put down by the operator, or by the shock of the next car.

By this arrangement the brakeman need not wait until the link is withdrawn in uncoupling, as the drop will remain up, leaving the link free to withdraw at any time. Again, the device is self-coupling in either case—*i. e.*, whether the drop is up (in which case it will be thrown down by the shock of the car) or down, (in which case the entering link will lift it, and it will fall by its own weight.)

The recess E', Fig. 2, serves to hold the outer end of the link from falling when one end only is in a draw-bar, thus holding the unengaged end in position for entering the mouth of the draw-bar of the next car.

I claim as my invention—

The combination of the draw-bar B and link D with the segmental holding-drop C, said drop being so made and hung that if turned up in a vertical position it will remain so until the concussion of the draw-heads shall throw it down and thus couple the cars, substantially as described, and for the purpose set forth.

JOHN H. BURRELL, JR.
